UNITED STATES PATENT OFFICE

95,142

DESIGN FOR A LUNCH BOX OR THE LIKE

Martin Nelson, Menlo Park, Calif.

Application January 10, 1935, Serial No. 54,796

Term of patent 7 years

To all whom it may concern:

Be it known that I, Martin Nelson, a citizen of the United States, residing at Menlo Park, in the county of San Mateo and State of California, have invented a new, original, and ornamental Design for a Lunch Box or the like, of which the following is a specification, reference being had to the accompanying drawing, forming part thereof.

I claim:—

The ornamental design for a lunch box or the like as shown.

MARTIN NELSON.
